GOLF RANGE FINDER

Francis X. Lo Jacono, 10548 S. Wedgeport,
Whittier, Calif.

Filed Feb. 17, 1965, Ser. No. 83,847

Term of patent 14 years

(Cl. D34—5)

Fig. 1.

Fig. 2.

Fig. 3.

Fig. 5.

Fig. 4.

Fig. 6.

FIG. 1 is a back elevational view of a golf range finder showing my new design;

FIG. 2 is a front elevational view thereof;

FIG. 3 is a side elevational view;

FIG. 4 is a side elevation view of the opposite side;

FIG. 5 is a top plan view; and

FIG. 6 is a front elevational view showing the device in an operating position.

The dominant features of the design reside in the portions shown in full lines.

I claim:

The ornamental design for a golf range finder, as shown and described.
